[57] CLAIM

The ornamental design for a dice scrambler, as shown and described.

DESCRIPTION

FIG. 1 is a front, top and left side perspective view of a dice scrambler embodying my new design;
FIG. 2 is an enlarged front elevational view thereof;
FIG. 3 is an enlarged right side elevational view thereof, the left side elevational view being a mirror image;

FIG. 4 is an enlarged rear elevational view thereof;
FIG. 5 is an enlarged top plan view thereof with the pins shown in broken lines for illustrative purposes only and form no part of my design; and,
FIG. 6 is an enlarged bottom plan view thereof.

FIG. 1

FIG. 2

FIG. 3

FIG. 4

FIG. 5

FIG. 6
